UNITED STATES PATENT OFFICE.

GEORGE A. TURNBULL, OF CHICAGO, ILLINOIS.

SHOE-FASTENING DEVICE.

SPECIFICATION forming part of Letters Patent No. 752,268, dated February 16, 1904.

Application filed April 23, 1902. Serial No. 104,400. (No model.)

To all whom it may concern:

Be it known that I, GEORGE A. TURNBULL, a citizen of the United States, and a resident of Chicago, in the county of Cook and State 5 of Illinois, have invented certain new and useful Improvements in Shoe-Fastening Devices; and I do hereby declare that the following is a full, clear, and exact description thereof, reference being had to the accompanying drawings, and to the letters of reference marked 10 thereon, which form a part of this specification.

This invention relates to improvements in shoe-fastening devices, and more particularly 15 to a lacing-hook of simple construction and designed to be used on ladies' shoes, as well as the shoes of men and of children.

The object of the invention is to provide a lacing-hook so constructed as to positively 20 prevent the lace of a lady's skirt or other garment or a thread of any kind being drawn through the hook after the shoe is laced.

The invention consists of the matters hereinafter described, and more fully pointed out 25 and defined in the appended claim.

In the drawings, Figure 1 is a perspective view of a shoe provided with a lacing-hook embodying my invention. Fig. 2 is an enlarged fragmentary detail of the same, illustrating the manner of lacing the shoe. Fig. 3 is a transverse section through a pair of the 30 hooks and illustrates the position the laces assume in the hook. Fig. 4 is a similar view illustrating in the left-hand side thereof one 35 position which the lace assumes in fastening and unfastening the same from the hook.

As shown in said drawings, A indicates a shoe as a whole, which may be of any style or construction, having secured thereon in the 40 usual manner the lacing-eyelets, (indicated by a,) extending upwardly over the lower part of the instep. Above said eyelets and on each side of the shoe-upper are disposed the hooks B, which as shown are formed integral with 45 the eyelets b and are bent transversely over the eyelet, forming a relatively flat low inwardly-directed hook. The free ends of said

hooks are turned under and inwardly and the extremities slightly upwardly, forming a bend near the free extremity of the hook which 50 presses down on the leather of the upper of the shoe in close proximity to the front or tongue margin thereof, (indicated by C.) Said inwardly-directed ends or tongues of the hooks are curved slightly upward, as shown 55 more fully in Figs. 3 and 4, the better to receive and retain the lace in the shoe and to prevent threads or shreds of the clothing finding their way beneath the hooks. Obviously 60 the eyelet, with the integral hook, as shown, may be stamped of a single piece of metal, with the hook portion forming a tongue extending radially therefrom. Said free end is then bent upwardly and over in the form 65 shown in Figs. 3 and 4 to provide the hook.

The operation is as follows: It is to be observed that the hooks project inwardly toward the tongue of the shoe, with the inwardly-directed end portion, or tongue portion thereof, located as shown. The shoe may be laced 70 as usual, drawing the laces beneath the hooks, as shown in Figs. 2, 3, and 4. When drawn beneath the hook, as shown in Fig. 4, a slight upward movement carries the lace over the free end of the tongue into the end of the 75 hook and into the bend thereof, as shown in Fig. 3, thus straining or drawing said hook inwardly and closing the uppers over the tongue. Obviously no thread of lace nor 80 shred of clothing can now possibly engage beneath the hook, inasmuch as said shred or lace engages first on the lace of the shoe, which causes the same to slide up over the hook, it being manifestly impossible for any part of the clothing to find its way into the 85 hook or beneath the hook. In unlacing the shoe, the lace is pulled first laterally, then downwardly, and then inwardly, thus releasing the same from the tongue of the hook and withdrawing the same from beneath the hook, 90 or, if preferred, the lacing being untied, the lacing may be drawn through the hook in a manner similar to drawing the same through eyelets.

Obviously many details of construction may be varied without departing from the principle of my invention.

I claim as my invention—

5 In a device of the class described the combination with an eyelet, of a hook thereon comprising a strip integral with the eyelet and extending transversely thereof to a point beyond the same and the free end of said strip
10 turned inwardly and upwardly, with the bend formed thereby closely engaging the shoe-
upper thereby forming a closed hook through

which the lace must pass while being fastened or unfastened, and having a retaining-recess therein between the upturned end and said hook for the lace when seated.

In testimony whereof I have hereunto subscribed my name in the presence of two subscribing witnesses.

GEORGE A. TURNBULL.

In presence of—

HENRY F. DITZEL,
ANNA B. HILLS.
